Primary Examiner—Alan P. Douglas*Assistant Examiner*—Robin V. Taylor*Attorney, Agent, or Firm*—Hedman, Gibson & Costigan, P.C.[57] **CLAIM**

The ornamental design for a traction hoist used in a powered suspended scaffold, as shown and described.

DESCRIPTION

FIG. 1 is front view of a traction hoist assembled with an electric motor;

FIG. 2 is a rear view of the traction hoist assembled with the electric motor;

FIG. 3 is a top plan view of the traction hoist assembled with the electric motor;

FIG. 4 is a bottom plan view of the traction hoist assembled with the electric motor;

FIG. 5 is a right side elevational view of the traction hoist assembled with the electric motor;

FIG. 6 is a left side elevational view of the traction hoist assembled with the electric motor;

FIG. 7 is a perspective view from the front and left side of the traction hoist assembled with the electric motor; and,

FIG. 8 is a perspective view from the front and right side of the traction hoist assembled with the electric motor.
